UNITED STATES PATENT OFFICE.

ETHELBERT FAVARY, OF NEW YORK, N. Y.

DRYING APPARATUS.

Application filed December 4, 1919, Serial No. 342,428. Renewed May 13, 1926.

This invention relates to apparatus for drying wet laundry of any kind or description in a very short time, without danger of burning such laundry.

5 My invention consists essentially of a structure composed of one or more inclined surface plates enclosed on all sides, with the exception of an opening for the admission of hot air arising from a flame or a heater 10 beneath the drying apparatus. The apparatus is self-contained without any connection for a flame within the apparatus itself, and the temperature within is substantially uniform all over, by making use of heated air 15 or gas to come in contact with the drying surface plates. In the accompanying drawing forming part of this specification, Figure 1 shows a cross sectional view; Figure 2, a sectional side elevation through A—A 20 of Figure 1; Figure 3, a cross section through B—B of a modified structure embodying my invention, and Figure 4 a side view of the same, partly in cross section through line D—D. Figs. 5 and 6 show 25 modifications of portions of the device. In the drawings, like letters represent like parts in all the figures.

a, a, denote a plurality of inclined surface plates, made of any suitable material, preferably, galvanized or enamelled sheet iron, or sheet iron, dipped in some anti-rust solution.

b is the bottom plate which closes the drier at the bottom except for an opening 35 *c* to admit the heat into the interior.

d, d, are end plates, which cover the ends of the inclined surfaces.

b and *d* may be made of any suitable material, preferably a non-conductor, to prevent 40 the dissipation of heat through the ends and through the bottom of the drier. If desired, *b, d*, may be made of metal, covered on the interior, or exterior, with a non-conducting material or a non-conducting 45 paint *y*, as shown in Fig. 2. *a, a*, are preferably made of material termed as a "good conductor", so that heat from the inside should readily be transmitted to the outside, which, when in use, is covered with the wet laundry.

50 It can thus be understood that in this drier, heated air or gas is relied on to keep the entire surface which is coming in contact with the wet laundry at a uniform temperature, and the entire space within the drier is enclosed, except where necessary to admit the heating medium; this heating

medium may be admitted from the bottom as shown, or through one or more openings in any portion of the apparatus. As the heat is chiefly, if not entirely, dissipated 60 through these inclined surface plates, which come in contact with the laundry, the heat units within the apparatus are used for useful work with a minimum of loss. This could not be accomplished if a flame 65 were directed against the surface plates *a, a*, for it would cause overheating of the metal in some portions of the apparatus; and if the device had an opening at the top, or at the sides, or were entirely open at the 70 bottom, a great deal of the heat would escape without doing any useful work.

To prevent the flame, or too great a heat, from touching the inside of the surface plates *a, a*, shields *f, f*, of any suitable material are interposed, wherever it is liable to cause overheating. When in use the drier is preferably placed directly over a burner of a gas range or any other heating means, the opening *c* resting over the flame. The 75 arrows *x* representing the flame or the heat entering the drier.

j represents a portion of the gas range with burners *k*, shown underneath the opening *c* of the drier.

85 Therefore, the flame will take the necessary oxygen for consuming the gas from without the apparatus, whereas the heating medium will rise directly into the drier and will, substantially, uniformly heat the interior of the entire apparatus. The shield plates *f, f*, may be composed of any suitable material and may consist of single plates, or of a plurality of plates with air spaces between the plates, as shown, or of metal, and 90 a non-conductor *n*, like asbestos, placed between it and the surfaces they are to shield. If desired instead of being made as shown, they may simply consist of asbestos sheets fastened directly to the surfaces wherever 95 the flame from the gas range may strike them or come too close to them, to prevent over-heating or hot spots as shown in Fig. 5. *s, s*, are supports by which the shields are held in place.

100 The drier may be made in sections, detachable, or collapsible as shown in Figures 3 and 4, to fold up when not in use. In Figures 3 and 4, *g, g*, show the central members of hinges where the inclined surfaces fold 105 together, while *h* shows a hinge or any other suitable attachment between the end plates *d*.

and the bottom plate *b*. Instead of hinges, any suitable construction may be employed to detachably connect the various plates with each other. The bottom plate can also 5 be hinged with *a* if desired, as shown in Fig. 6, or in any convenient manner, or it may be curved around the edges as shown at *i*, so as to be in sliding connection with some of the surface plates *a*, *a*. It is understood, of 10 course, that the end plates *d*, the surface plates *a*, and the bottom plate *b*, may be attached with each other either rigidly or in any known collapsible or detachable manner as is evident to anyone skilled in the 15 art.

In the arrangement shown in Figures 3 and 4, the four inclined surface plates are in hinged connection with each other, while the end plates and the bottom are hinged 20 together. If desired to disassemble the drier when not in use, it is only required to take off nuts *o* and unhook catches *p* when the four inclined surface plates can be folded together, and the bottom plate 25 and the end plates can be folded up. When assembling, the bottom plate and the end plates may be placed flat on a table; then the surface plates *a*, *a*, are placed in position with the two outermost plates inside *i* of the 30 bottom plate, then the two end plates are folded upward and are attached to *a*, *a*, by means of catches *p* or nuts *o*, or any other suitable means.

If desired, the outside of the surface 35 plates *a*, *a*, may be covered with a wire netting or any other material to keep the wet laundry a certain distance from the said plates. This arrangement would however, not be as efficient as where the laundry comes 40 in direct contact with the heated surface plates. At *m* is shown a projection running along the lower ends of the surface plates to prevent the laundry from reaching down to the top of the gas range, and at the same time 45 it may serve to lead away the dripping water which may come down from the wet laundry. Since there is no burner with the apparatus, no outlet is required for the burned gases, and in this manner the heat 50 within the device is used to the best advantage. A small opening *r* may be provided at or near the bottom to observe the flame for adjustment, or to note if the shields are becoming overheated, in which case the gas 55 flame may be turned lower, since only a very small flame is required. If desired this opening may be covered by means of a piece of mica or other suitable transparent material. Even if open comparatively little, heat would escape because it is located near 60 the bottom.

If found convenient, any suitable means 65 may be provided for keeping the laundry taut while being dried and thus obviate the necessity of ironing it afterwards. This

may be found especially useful for handkerchiefs, towels, and the like. When not in use a hook or catch provided on the drier can be employed to hang the device up on the wall. If desired, the bottom may be 70 closed up entirely, in which case the heat may be made to enter the device by heating the bottom plate. The shields, as seen from Figure 3, may be attached to the bottom or they may be formed of one piece with the 75 bottom plate.

Having now described my invention, what I claim as new and desire to protect by Letters Patent is—

1. In a drier a plurality of inverted V- 80 shaped metallic surface plates composing the outside of the drier and a bottom plate with an aperture for admitting a heating medium from a heating device from without the apparatus for heating the inner 85 side of said surface plates, their outer side being used for drying.

2. In an apparatus for drying, inclined surface plates, the device closed on all sides but one which has an opening for the admission of a heating medium from without the apparatus. 90

3. An apparatus for drying, having a plurality of inclined surface plates closed at their ends, means for heating the inner 95 sides of said surface plates, their outer sides being used for drying, a shield for preventing portions of the surface plates from becoming overheated.

4. A drier having a plurality of inclined surface plates, means for heating the inner sides of said surface plates, their outer sides being used for drying and a plurality of shields to prevent the inclined surface plates 100 from becoming overheated. 105

5. A drier composed of a plurality of inclined surface plates, collapsibly connected together, the surface plates forming the outside of the device and means for heating such surface plates. 110

6. A drier composed of a plurality of collapsible surface plates and end plates for closing the ends of the surface plates.

7. A drier composed of a plurality of inclined surface plates collapsibly connected together, means for heating said surface plates, and a shield to prevent the surface plates from becoming overheated. 115

8. A drier composed of a plurality of inclined surface plates collapsibly connected together, end plates to close such surface plates, and means for admitting a heating medium into the device from without. 120

9. In a drier, a plurality of collapsibly arranged inclined surface plates, the device substantially closed on all sides, one of the sides having an opening for admitting a heating medium from without. 125

10. A drier composed of a plurality of collapsible surface plates, means for heating 130

the surface plates and for closing the ends of such plates, and a shield for preventing the surface plates from becoming over-heated.

5 11. A drier, composed of a plurality of inclined surface plates collapsibly connected together, the drier substantially closed on all sides, means for heating the device from without.

10 12. In a drier, inclined surface plates, means for admitting a heating medium to the interior of the device, means for substantially conserving said heating medium.

13. In a drier, inclined surface plates,

means for heating the surface plates and for 15 substantially conserving the heating medium used for heating said surface plates.

14. In a drier, inclined surface plates, means for admitting a heating medium into the interior of the device from without for 20 the purpose of heating the surface plates, and means for substantially preventing the loss of the heating medium except through said surface plates.

Signed at New York in the county of 25 New York and State of New York this third day of Dec. A. D. 1919

ETHELBERT FAVARY.
